United States Patent Office

Des. 183,864
Patented Nov. 4, 1958

183,864

DRAPERY HOOK

Sidney Schwartz, Detroit, and Harold E. Guenther,
Plymouth, Mich.

Application March 17, 1958, Serial No. 50,054

Term of patent 14 years

(Cl. D17—12)

Fig. 1 is a front elevational view of a drapery hook embodying our new design;

Fig. 2 is a side elevational view thereof;

Fig. 3 is a bottom plan view; and

Fig. 4 is a top plan view thereof.

We claim:

The ornamental design for a drapery hook, substantially as shown.
